UNITED STATES PATENT OFFICE.

WILBUR T. CLARK, OF CLEVELAND, OHIO, ASSIGNOR, BY MESNE ASSIGNMENTS, TO THE HANNA FURNACE COMPANY, A CORPORATION OF DELAWARE.

COMBINED CLEANING-DOOR AND CHIMNEY-VALVE.

1,390,669.

Specification of Letters Patent. Patented Sept. 13, 1921.

Application filed February 24, 1919. Serial No. 278,766.

To all whom it may concern:

Be it known that I, WILBUR T. CLARK, a citizen of the United States of America, residing at Cleveland, in the county of Cuyahoga and State of Ohio, have invented certain new and useful Improvements in Combined Cleaning-Doors and Chimney-Valves, of which the following is a specification.

My invention relates to improvements in combined cleaning door and chimney valve especially designed for use with hot blast stoves, and has for its object the provision of a strong and effective structure of this class which shall be easily and conveniently operated, while affording at all times the opportunity for inspection and ready repair or replacement.

Hotblaststoves commonly have utilized separate and somewhat cumbersome means for cleaning them and for operating the connections to the chimney stack. These means, moreover, have not afforded adequate facilities for inspection and ready repair. Accordingly, I have endeavored to meet practical requirements by combining such means, preferably in a single structure for equipping hot blast stoves and the like.

My improvements as herein embodied and illustrated, may be briefly described as comprising a massive main frame or casting adapted to be set into the base of the hot blast stove, which casting preferably is provided with a removable valve-seating member. Its co-acting valve-member is equipped with actuating means adapted alternatively to force it home to its seat or close the external opening through which inspection is afforded.

A removable front and an insertible protective shield for the duct to the chimney stack are provided for cleaning out the stove and facilitating replacements and repairs. Moreover, the relatively heavy or massive movable members preferably are hinge-mounted, suitably supported for actuation and equipped with assembling members to avoid breakage.

My invention may be better described in its preferred embodiment by making reference to the accompanying sheets of drawings illustrating such embodiment, where in:—

Figure 1 is a view in front elevation partially broken away, showing the combined cleaning door and chimney valve for hot blast stoves, embodying my improvements.

Fig. 2 is a vertical sectional view thereof on line 2—2 of the preceding figure.

Fig. 3 is a plan view of my improved structure, shown broken away in the lower lefthand corner.

Fig. 4 is a fragmentary section taken on line 4—4 of Fig. 1.

Fig. 5 is another fragmentary section taken on line 5—5, of Fig. 1 showing the valve-supporting means and a spacing member.

Fig. 6 is a fragmentary section on line 6—6 of Fig. 3.

Throughout the several figures of the drawings, I have employed the same character of reference to indicate similar parts or elements.

Referring first to the vertical section, it is seen that the several members are mounted upon the massive casting *a*, to which is bolted the annular valve-seat member *b* and the duct *c* leading to the chimney stack, while above the latter, the casting *d* forms a casing inclosing the valve member *e*. The latter is provided with an annular beveled face bearing snugly against the valve opening, and is interiorly insulated by asbestos packing *e'*, or is otherwise suitably protected against intense heat.

Bolted securely to the upper and lower casing members, *d*, *f*, is the annular closure *g*, against which the valve member *e* is adapted rearwardly to be drawn by its threaded stem *e''*. This stem is carried by a spider *h''* and hinged yoke *i* swinging from the right hand side of castings *d*, *f*, on the loose-pin hinge *i'*. The outer end of the stem *e''* is threaded into the tapped hand wheel *j*, which serves to actuate the valve member into its front and rear positions.

The casting forming said valve member *e*, being of large size and heavy construction, is provided with two roller members *k* bearing upon adjustable supports *k'*, *k''*, attached at front and rear interiorly of the casing. Accordingly, this heavy valve member is readily actuated and accurately seats the front and rear valve openings; being forced to its place by the threaded stem and hand wheel.

In order to relieve the casing members from strain, the yoke *i* is provided with lateral bolts *l* which are interiorly attached to the massive casting *a* by the self-locking gib-keys *l'*. These bolts pass through the spacing members *m* which are terminally

threaded and rearwardly screwed into the valve member *b* at either side of the valve opening, and when properly adjusted said members *m*, as shown in Fig. 6, are locked in position by jamb-nuts *m'*. Thus the strain from the nuts *l''* when tightened on bolts *l* and yoke *i*, is carried directly to the spacing members *m*, which are sleeved upon the bolts *l*, and the casing is relieved from compression strains tending to break the casing members were this not provided against by the structure set forth.

The valve *h* or damper member in the duct *c* leading to the chimney stack may be operated by the handle *h'*. This is provided with a temporary covering or shield in the form of a sector *o* fitting beneath the valve openings and valve member *e*. Said shield or covering *o* serves to prevent any material from falling into the duct *c* during cleaning operations, and it is positioned above said duct for this purpose only during such operations. It may readily be disposed in the dotted line position of Fig. 1 when the casing is open.

In order to facilitate cleaning and afford free access to the valve-seat, as well, after removing the peripheral securing bolts *p* and clips *p'*, the nuts *l''* are first taken from the bolts *l*, so they may be pushed back to release the gib-keys, and permit the bolts to be withdrawn, whereupon the entire yoke and spider may be swung back approximately to an angle of 180° upon the hinge at the right. This affords free access to the interior of the structure. Under these conditions, a thorough cleaning is readily accomplished or the interior of the structure is laid open for inspection.

Should it be found necessary at any time, the valve-seat member *b* and its co-acting valve member *e* may be removed for refinishing or replacement; substitute counterparts immediately being installed in order to avoid any continued shut down of the associated hot blast stove.

In practice it is found that the pressure within the stove exerted upon the intensely heated products of combustion tends to destroy the effectiveness of the valve closure. Accordingly, it is quite essential that the valve and valve parts shall be open to inspection, and in my improved structure these may be viewed through the aperture 55 in the outer closure *g*, open to the external air when the valve is closed. Thus any escape of the hot gases may at once be detected.

Constructed and mounted as shown, all operative parts are most easily and quickly actuated, while undue strains are provided against in forcibly seating the valve member, as is necessary in structures of this class.

It will be understood that when the chim-

ney valve is opened, valve member *e* will close the central opening in *g*, while the duct leading to the chimney stack will be cleared by actuating handle *h'* and opening damper *h* to permit the escape of the products of combustion to the chimney.

Having now described the preferred embodiment of my invention, I claim as new and desire to secure by Letters Patent, the following:

1. In a structure of the class described, 75 the combination with a massive frame-casting, of a casing open to the atmosphere, a removable valve-seat attached to said casting, a co-acting valve member, a yoke, actuating means for said valve member mounted 80 upon the yoke, securing means therefor extending to the frame-casting, and spacing members for relieving any abnormal strains upon the casing, substantially as set forth.

2. In a structure of the class described, 85 the combination with a frame-casting, of a removable valve-seat member provided thereon, a casing having an opposing opening to the atmosphere, a chimney stack connecting with the casing, a valve member 90 adapted alternatively to engage said seat or close the opening, means for actuating the same, and a hinged support for the front of said casing and valve member, substantially as set forth.

3. In a structure of the class described, the combination with a frame provided with a valve-seat, of a sectional casing, a valve member within the casing and adapted to be engaged with said valve-seat, actuating mechanism therefor, and supporting means for said valve member mounted upon the frame independently of the casing, and actuating mechanism, substantially as set forth.

4. The combination with the gas outlet of 105 a stove or the like, of an inclosing casing affording an accessible cleaning opening opposite said outlet, a valve member adapted alternatively to close the outlet or the cleaning opening, and means for actuating said 110 valve member, substantially as set forth.

5. The combination with the gas outlet of 115 a stove or the like, of an inclosing casing affording a connection to the chimney stack, a valve member adapted to close said outlet, means for actuating said valve member, and an additional valve member controlling the outlet to the chimney stack, substantially as set forth.

6. The combination with a valve seat disposed in vertical position to form the gas outlet of a stove or the like, of a vertically disposed closure member therefor, supports or ways whereon said member is adapted to travel, and actuating mechanism for said 125 closure member, substantially as set forth.

7. The combination with a frame equipped with a valve seat and forming the gas out-

let of a hot blast stove or the like, of a co-
acting closure member, actuating mechanism
therefor, a hinged support for said member
and its actuating mechanism, and means
5 connecting said support directly with the
frame, whereby the strains initiated by the
actuating mechanism are conveyed directly
to the frame, substantially as set forth.

8. The combination with a frame having
10 a valve seat and forming the gas outlet of
a hot blast stove or the like, of an inclos-
ing casing affording an inspection opening
opposite said valve seat, a closure member
adapted alternatively to close the outlet or
15 the inspection opening, actuating mecha-
nism therefor, a hinged support for said
member and its actuating mechanism, and
a damper controlling the stack connection
from the casing, substantially as set forth.
20 9. The combination with a valve-seating
member affording a lateral opening to a
stove, furnace or the like, of a closure part
adapted to be seated thereon, actuating
mechanism therefor, a casing positioned
25 about said valve-seating member but open at

the front to permit access for inspection
and cleaning, a shield positioned within the
opening in said casing, and means tempo-
rarily securing it thereto, substantially as
set forth.

10. The combination with a frame
equipped with a valve-seating opening to a
stove, furnace or the like, of a valve mem-
ber, means for actuating said member
against its seat, a casing partially inclosing
35 the valve-seating opening and its valve, a
casing open at the front to afford free ac-
cess thereto, actuating means for the valve,
a closure normally positioned within the
opening in said casing, and a hinged yoke
40 supporting the valve, its actuating mecha-
nism and the closure, substantially as set
forth.

In testimony whereof I do here affix my
signature in the presence of two witnesses. 45
